UNITED STATES PATENT OFFICE.

FREDERICK B. COOK, OF NEW YORK, N. Y.

MAIL-CHUTE.

1,293,345.

Specification of Letters Patent.

Patented Feb. 4, 1919.

Application filed June 12, 1914, Serial No. 844,770. Renewed March 28, 1918. Serial No. 225,382.

To all whom it may concern:

Be it known that I, FREDERICK B. COOK, a citizen of the United States of America, and resident of the borough of Manhattan in the city of New York, county and State of New York, have invented certain new and useful Improvements in Mail-Chutes, of which the following is a specification.

In mail-chutes of that type in which the front of the chute is removable in sections, the same being attached by means of a plurality of hooks upon the removable sections which enter corresponding openings in the body of the mail-chute, difficulty has been experienced in conveniently removing, handling and replacing the removable front-wall sections. The object of the present invention is to provide means for reducing the handling and care of the front-wall heretofore necessary, and permitting the same to be readily replaced in position upon the body of the chute. For this purpose the front-wall is hinged at one of its vertical edges to the body of the chute, and the hinges are so made as to permit a limited vertical movement of said front-wall whereby the hooks of the same may be disengaged from and reengaged with the body of the chute. The hinges are also so constructed as to support the front-wall in raised position, so that when the same swings into closing position, it is at the same time in raised position and the hooks readily enter the openings provided for them.

35 In the accompanying drawings,

Figure 1 is a front-view of a mail-chute embodying the invention,

Fig. 2 is a front-view of a portion of the chute, showing one of the front-wall sections in open position,

Fig. 3 is a horizontal section on line 3—3, Fig. 1, on an enlarged scale,

Fig. 4 is a horizontal section, showing the front-wall in open position,

Fig. 5 is a detail of the hinge,

Figs. 6 and 7 show the front-wall disengaged from and engaged with the body of the chute respectively, and

Fig. 8 is a horizontal section on line 8—8, Fig. 1, on a larger scale, showing the locking member by which the individual front-wall sections are locked against removal.

Similar reference numerals indicate corresponding parts throughout the several views.

The body of the chute comprises a rear-

wall 10, side-walls 11 and 12, and jambs 13, 14 formed at the front-portion of the side-walls by inturning the metal thereof. The front-wall is composed of a number of vertical sections of convenient height, each comprising a frame having side members 15, 16 between which the glass panel 17 is held, and from which project inwardly-down-turned hooks 18 which are adapted to engage correspondingly-spaced openings 19 in the jambs 13, 14 of the body of the chute.

To the body of the chute are secured by any suitable means the pintle-sections of two hinges 20, 21, the corresponding leaf-sections of which are secured to the section 22 of the front-wall which is to be supported. Each pintle-section comprises a lower supporting member 23, an upper supporting member 24, and a pintle 25 between said upper and lower members. A screw 26 in the upper member 24 secures the upper end of the pintle, while two screws 27 in the lower member 23 secure the lower end of the pintle and prevent its rotation. The pintle is provided at its upper portion with two vertical recesses 28, 29, oppositely arranged, and so arranged as to receive, when the front-wall section 22 is in closed position, an inwardly-projecting lug 30 of the leaf member 31 of the hinge in the recess 28. When the front-wall section 22 is in open position, said lug 30 is received in the recess 29 of the pintle. When the front-wall section is in an intermediate position, said lug 30 rests upon the top of the enlarged portion of the pintle, and thereby supports the front-wall section 22 in raised position, as indicated in dotted lines in Fig. 5.

When the front-wall section 22 is in closed position, as is seen in Fig. 1, it is retained against vertical movement by a locking member 40, comprising a cross-bar within which a suitable locking mechanism is operated by a key through the keyhole 41 at the center of the bar adapted to throw the bolts 42 laterally outwardly into openings 43 in the jambs 13, 14. The bolts thereby hold the locking member in position, while the member itself is arranged vertically in the same plane with the front-wall section 22 and close across the top thereof, as seen in Fig. 1, so that any lifting of the front-wall section 22 is rendered impossible by its abutment against the locking member.

When it is desired to open a section of the chute for any purpose, the locking member

40 located above the section to be opened, is unlocked and removed. The section 22 is then bodily lifted, which is permitted by the vertical play in the hinges 20 and 21, where-
 5 by the lug 30 is raised out of the slot 28, and upon the front-wall section now being partially opened, said lug rests upon the top of the enlarged portion of the pindle 25. Upon now swinging farther open the section 10 22, the same is finally brought into the position shown in Fig. 4. In this position the lug 30 is brought opposite the recess 29, which it enters, thereby lowering the section 22 and locking the same against rotation in either direction. The section 22 is thereby held out of the way of workmen who may be engaged in repairing the chute or in clearing the same, does not require to be bodily set to one side and care taken of it lest it 15 fall and be broken—as is the case in chutes having completely detachable sections, is always retained in connection with its own proper portion of the body of the chute, so that there is never any question as to which 20 particular part of the chute any particular section of front-wall belongs upon, and is conveniently held ready for prompt replacement when desired. For closing the section 22 upon the body of the chute, the section is 25 lifted so as to cause the lug 30 to clear the recess 29 and the section is then swung back into closed position, the same being supported, until in close proximity to the jamb 13, by the lug 30 riding upon the enlarged 30 portion of the pindle 25. In this raised position the hooks 18 are opposite the upper part of the openings 19, as seen in Fig. 6. Upon finally closing the section 22 against the jamb 13, the hooks 18 enter the openings, 35 the lug 30 enters the recess 28, and the section 22 is free to drop, which it does, the hooks 18 guiding by their beveled inner faces 44 the front-wall section 22 into close contact with the jamb 13 and retaining the 40 same in such contact, as indicated in Fig. 7. The locking member 40 may now be replaced and that particular portion of the chute is again in condition for use.

The hinges described, by retaining the 50 front-wall section in proximity to the body-portion and at the same time preventing the same from closing during the operations carried on upon the chute, increase the facility of repair and inspection of the chute, and enhance the usefulness of the chute as a means of collecting mail.

One embodiment of the invention has been described, but it is obvious that changes may be made therein without departing from the 60 spirit of the invention as set forth in the claims.

I claim:

1. A mail-chute, comprising a body portion, consisting of a rear and side walls, a 65 front wall, means securing said front wall to

said body portion, said means adapted to become disengaged upon upward movement of said front wall, hinging means adapted to support and permit swinging of said front wall upon disengagement from said body portion, and means on said hinging means adapted to permit lowering of said front wall when swung through a predetermined angle relatively to said body portion, said means adapted to positively prevent swinging of said front wall in either direction in said lowered position.

2. A mail-chute, comprising a body portion having jambs at its front edges, a series of openings in said jambs, a front wall section having at its edges a series of downturned hooks spaced to enter said openings of said jambs, and a hinge connection between said body portion and said front wall section, comprising a pindle member 85 having an enlarged portion and two vertical slots therein, and a leaf member having a lug adapted to engage said slots, said pindle being of such length as to permit the vertical movement of the leaf member thereon sufficiently for the disengagement of said hooks from said openings, and said slots being so located as to receive the lug of the leaf member when the front wall section is in closed position and when the same is in one position of opening.

3. A mail-chute, comprising a body-portion having jambs at its front-edges, a series of openings in said jambs, a front-wall section having at its edges a series of down-turned hooks spaced to enter said openings of said jambs, two hinges connecting said body-portion and said front-wall section, one hinge at the upper portion of the section and one hinge at the lower portion 105 thereof, each hinge comprising a pindle member having an enlarged portion and two vertical slots therein and a leaf member having a lug adapted to engage said slots, said pindle being of such length as to permit the vertical movement of the leaf member thereon sufficiently for the disengagement of said hooks from said openings, and said slots being so located as to receive the lug of the leaf member when the front-wall section is in closed position and when the same is in one position of opening.

4. A mail-chute, comprising a body-portion having jambs at its front-edges, a series of openings in said jambs, a front-wall section having at its edges a series of down-turned hooks spaced to enter said openings of said jambs, two hinges connecting said body-portion and said front-wall section, one hinge at the upper portion of the section and one hinge at the lower portion thereof, each hinge comprising a pindle member having an enlarged portion and two vertical slots therein and a leaf member having a lug adapted to engage said slots, said pindle 120 125 130

being of such length as to permit the vertical movement of the leaf member thereon sufficiently for the disengagement of said hooks from said openings, and said slots 5 being so located as to receive the lug of the leaf member when the front-wall section is in closed position and when the same is in one position of opening, and a transverse locking member extending 10 across the body-portion immediately above said front-wall section and in the same vertical plane therewith, and having means for locking the same against vertical movement to the jambs at either side of the body-portion. 15

5. A mail-chute, comprising a body portion provided with jambs at its front edges, a front wall portion adapted to engage said jambs, one of said portions having a series 20 of openings, and the other a series of hooks adapted to enter said openings, and a hinge connection between said body portion and said front wall portion, said hinge connection comprising a pintle member and a leaf 25 member, one of said members being provided with two vertical elements, and the other with an element adapted to register with the first named elements, the elements on the two members being respectively of 30 the lug and slot character, said pintle being

of such length as to permit a vertical movement of the front wall sufficient to disengage said hooks from the corresponding openings, and said two elements on the one member being so located as to register with the element on the other member when the front wall is in closed position and when it is in one position of opening. 35

6. A mail-chute, comprising a body portion and a front wall portion adapted to engage said body portion, a hinge connecting said front wall portion with said body portion and permitting vertical movement of the front wall portion relatively to the body portion, and mating hooks and openings 40 provided on said portions, the hooks having beveled faces to cause the front wall portion to perform a final swinging movement on its hinge as said front wall portion moves vertically to the closing position, to draw 45 said wall portion into tight engagement with the body portion. 50

In testimony that I claim the foregoing as my invention, I have signed my name in presence of two subscribing witnesses.

FREDERICK B. COOK.
